NECKTIE CONSTRUCTION

Max M. Newman, New York, N. Y.

Application January 15, 1946, Serial No. 641,203

10 Claims. (Cl. 2—146)

1

This invention relates to linings for neckties and more particularly to such linings which produce a controlled drape when the necktie is tied.

When a tie is made up, it is desirable to produce an indentation or valley in front of the necktie just below the knot. Such an indentation should be centrally located and serves to give the tie a more pleasing appearance. As far as I am aware, previous efforts to accomplish this objective generally involved modification of the shape or configuration of the lining. For example, weakening slits, re-enforced sides, stiffeners, or gathered areas were used to cause the desired bulging for the purpose desired. The present invention, however, involves as an object thereof, the production of a necktie lining which produces the desired indentation by the very character of the lining fabric. Thus, aside from a special method of producing the material of which the lining is made, no physical modification of the lining is necessary to produce the indentation. Since the function of a tie lining is to prevent undue distortion of the tie substantially throughout its area, the present means for securing the desired indentation does not interfere with this objective because the lining may be made so as to be hardly distinguishable physically from an ordinary lining while its special characteristics will appear only when the tie is made up. The tie lining in one embodiment of the instant invention is formed with neither cut-outs nor stiffening members or the like so that no portion of the tie is not given the benefit of the usual forming foundation supplied by the conventional tie lining.

Another object of this invention is to provide a necktie lining which although apparently unitary in nature, actually is composed of distinguishable areas each serving to apply a special formation to the tie to which the lining is connected.

Another object of this invention is to provide a tie lining which only manifests tie shaping characteristics when the tie is pulled as in the process of being made up, the lining being further of a resiliency which restores it to a planar state when the tie is not thus made up.

Other objects of my invention will be apparent from the following description, it being understood that the above general statements of the objects of my invention are intended to describe and not to limit it in any manner.

Referring to the drawings:

Fig. 1 is a bottom plan view of a necktie lining illustrating one embodiment of my invention.

2

Fig. 2 is a top plan view thereof.

Fig. 3 is a cross-sectional view of Fig. 1 taken diagonally on the angle of bias and when the lining shown therein is in a taut or pulled condition.

Fig. 4 is a plan view of the necktie lining shown in the previous figures as applied to a necktie, the rear, or folded over portions of the tie being omitted for the sake of clarity.

10 Fig. 5 is a plan view of a piece of fabric illustrating diagrammatically the production of tie linings of a composite nature for use in another embodiment of the invention.

15 Fig. 6 is an enlarged view of alternate sections of Fig. 5 and illustrating a lesser number of uppermost warp threads than of lowermost warp threads in relation to the filler threads.

20 Fig. 7 is a view similar to Fig. 6 but with the woven fabric thereof reversed in that the upper warp threads predominate.

25 Fig. 8 is a plan view of a necktie lining having end sections according to Fig. 6 and a central section according to Fig. 7.

30 Fig. 9 is a view similar to Fig. 8 but having the end sections similar to Fig. 7, and the central section similar to Fig. 6.

35 Fig. 10 is a cross-sectional section of the necktie lining shown in Fig. 8 taken on the angle of bias and when the lining is in a taut or pulled condition.

Fig. 11 is a plan view of a necktie lining illustrating still another embodiment of my invention.

40 Fig. 12 is a cross-sectional view thereof taken on the angle of bias and when the lining is in a taut or pulled condition.

Fig. 13 is an elevational partly broken-away view of a necktie supplied with a lining illustrating still another embodiment of my invention.

45 Fig. 14 is a rear view thereof.

Fig. 15 is a plan view of the necktie shown in Figs. 13 and 14, the tie being in the stretched-out state, the outer portion thereof being shown.

Fig. 16 is a view taken on the lines 16—16 of Fig. 13.

Fig. 17 is a separate view of the shaping element for the tie lining and illustrating the concavo-convex formation thereof under the influence of a pulling force.

50 Referring to Figs. 1 to 4, the necktie lining is illustrated as being made up of three separate sections connected side by side by lines of stitching 21 and 22. Each of the three sections 23, 24 and 25 is bias-cut so that the composite lining will stretch in a longitudinal direction under the

influence of a pulling force applied thereto. The material of which the sections are formed is a woven fabric having a special character of weave. This weave is such that warp threads are denser or more numerous on one side of the filler than on the other. As illustrated in Fig. 3, and as will be more fully set forth in the discussion of Figs. 6 and 7, the warp threads W_1 are twice as dense in number as the warp threads W_2 . In other words, two warp threads W_1 occur for every one warp thread W_2 throughout the weave. I have discovered that when a material of this nature is bias-cut and subjected to a pull, it will flex so as to become convex on the side of the denser warp threads and concave on the side of the warp threads of lesser frequency. Accordingly, section 24 as shown in Fig. 1 has the warp threads W_1 uppermost while the sections 23 and 25 have their warp threads W_1 lowermost. The reverse view as shown in Fig. 2 reverses the distribution in that section 24 there has the warp threads W_2 uppermost while the sections 23 and 25 have the warp threads W_1 uppermost.

It will be seen, therefore, that when the necktie lining as shown is pulled, it will assume an undulating shape in which the concavity of the central section opposes that of the end sections. It will be apparent that this shape results from the predetermined disposition of the denser warp threads where either convexity or concavity is desired, the disparity of disposition of the respective series of warp threads W_1 , W_2 on the respective sides of the material producing the controlled bend through the interaction of the threads, and no discontinuities in the form of openings or gatherings being required.

In Fig. 4 which illustrates the application of the described tie lining 20 to a necktie 26, the lining is so disposed that section 24 has the denser warp threads W_1 facing the rear of the tie so that the less dense warp threads W_2 face the front wall of the tie. The other sections are disposed according to the distribution illustrated in Fig. 3. It will be understood, therefore, that when the necktie as shown in Fig. 4 is subjected to a pull, the central portion thereof as controlled by section 24 will produce a recess throughout the length of the pulled area and centrally thereof. This recess will be emphasized or accentuated by the convex portions of the tie effected by the concavo-convex shape of sections 23 and 25, reversed relative to the section 24 to produce the undulating effect.

As will be hereinafter set forth, the tie is given its flexed state under the influence of such a pull as results from the normal action of making up the tie as it is to be worn by the user so that the desired indentation or valley only appears during such time and remains while the tie is being worn.

Fig. 5 illustrates a piece of "twill" or "drill" material in which the alternate stripe-like sections thereof correspond either to the disposition of warp threads as in W_1 or the reverse and less dense disposition represented by W_2 . The extent of the sections is represented by the imaginary lines L which indicate a change of the weaving pattern as hereinafter described. If desired, a jacquard type of weave having alternate longitudinal sections of loosely and tightly woven surfaces respectively, with the patterns alternating, may be employed.

Fig. 6 is a greatly enlarged view wherein the warp threads W_2 are uppermost and are woven together with the denser warp threads W_1 around

filler threads F. Fig. 7 which is a reverse view of Fig. 6 illustrates the reverse disposition of these threads. Each section of one side of the material shown in Fig. 5 is woven to correspond with the pattern of either Fig. 6 or Fig. 7, and for the sake of simplification, such sections or sides will hereinafter be referred to as sections or sides 6 or 7, depending upon the disposition of the warp threads. Thus, in the material shown in Fig. 5, the sections 6 and 7 follow each other alternately so that portions of the material can be cut out thereof which will incorporate three sections of the desired sequence for use as the improved tie lining. The material may, therefore, be cut along the lines C which extend diagonally across every other section, producing composite linings having the more dense warp threads represented by 7 as the central section thereof. Each tie lining appears, therefore, as illustrated in Fig. 8. Were the material to be reversed, the tie lining would appear as illustrated in Fig. 9. It is not believed necessary to illustrate the needle arrangement and design required to produce the weave of Fig. 5 since such arrangement will be apparent to those skilled in the art.

When a tie lining, bias-cut and having the illustrated side by side connection of sections 6, 7, 6 is pulled, the lining will produce three bends as illustrated in Fig. 10, the sections 7 thereof always being convex, while the sections 6 always become concave. In Fig. 10, as in Fig. 3, the central section may be considerably narrower than the end sections and the concavity will nevertheless be suitable or even superior than that illustrated.

The linings illustrated in Figs. 8 and 9 are applied in a conventional manner to an ordinary necktie, a sewed connection to the tie being made centrally of the composite lining as illustrated in Fig. 4.

In Fig. 11 is illustrated a composite lining wherein only the central section is of the special character of weave required to produce the controlled drape thereof. The central section having the side 7 uppermost is connected by lines of stitching 30 and 31 to a simple over-and-under woven material wherein the warp threads are equally distributed on either side of the filler threads F. The central section has its less dense side 6 lowermost. Accordingly, when the lining is pulled it will assume the shape illustrated in Fig. 12 wherein the controlled drape is substantially confined to the central section which, as in the previous embodiments, becomes concavo-convex on sides 6 and 7 respectively. It is applied to a tie as are the previous embodiments.

In the embodiment shown in Figs. 13 to 17, a channel-shaped element 35 is sewn to a conventional bias-cut lining 36 by a line of stitching 37. Element 35 is of the special weave above set forth, the side 6 thereof facing the front of the tie while the side 7 faces the rear thereof. Whereas tie lining 36 is of an ordinary weave which possesses no controllable drape characteristics, its connection to element 35 is such as to urge the central portion thereof into the concavo-convex shape assumed by element 35 when the tie is pulled. This shape will be further imparted to the body of the tie itself so as to produce the central indentation or dimple 38 as the tie is pulled when being made up. The shape accorded the tie is illustrated in Fig. 16 showing the indentation as controlled by the shaping element 35, the tie T responding to such control by producing a central valley 38 which is thereafter fixed in position by the tie knot.

The action of element 35 is shown in Fig. 17 where the side 6 is rendered concave by pulling on the ends of the element. Such pulling may be effected during the normal make-up of the necktie or may be deliberately applied to produce the desired result.

It will be seen from the above that I have produced a tie lining which shapes the tie by virtue of the special characteristics thereof produced by the weaving pattern, but it will be obvious that many changes and omissions may be made without departing from its spirit. The threads of which the lining is made may be of wool, mohair, or any other conventional tie lining material and, if desired, the warp threads thereof may be heavier and of larger diameter than the filler threads.

The invention thus takes advantage of the distortion characteristics of special materials while controlling these characteristics. The tendency of tie linings to distort and bend under the influence of a pull has long been guarded against in the necktie lining art and tie linings are generally rejected if they manifest such tendencies. This invention, however, makes use of materials which were hitherto considered defective and applies them so as to take advantage of the so-called defects.

In tie linings comprising, in effect, three longitudinal sections, the principles of the invention herein may be served by forming the two end sections of the special weave set forth herein, while the central section may be of an ordinary weave and not in itself subject to a controlled drape. Its association, however, with the controllable end sections will produce a virtual concavity therein for the desired purpose. Similarly, an elongated strip of material having the same weave throughout embodying a greater density of threads on one side than on the other or in any other manner providing a material of predetermined bending characteristics, may be utilized if means are incorporated therein for disabling a central section so as to remove its controlled bending characteristics. For example, the central section of the uniformly curlable fabric without a twill weave may be formed with longitudinal slits centrally thereof. Such slits would weaken the central portion of the lining so as to prevent its threads from effecting a central bend or concavity. The end sections, however, would maintain their bending or curling characteristics and would bend in the same direction in the required manner. The end section bends would, therefore, produce the effect of a reverse bend in the center or, in any event, the weave of the central section would be so affected that a distinctive area would be presented which does not follow the drape of its adjacent sections. In either event, a central concavity would be encouraged. In view of these, and other changes which do not depart from the spirit of the invention, it is described that the invention be limited only by the scope of the appended claims.

I claim:

1. A tie lining structure comprising a layer of woven fabric material cut on the bias, said material including a first series of threads and a second series of threads, said first series of threads occurring in greater frequency on one side of said fabric than said second series of threads on the other side thereof so that the material assumes a bend when pulled, said bend producing a concavity in a predetermined one of the sides of said material.

2. A tie lining structure comprising a bias-cut fabric material, said material including warp threads appearing on both sides thereof, the warp threads on one side of the material being more numerous than the warp threads on the other side of the material so that said structure assumes a longitudinal bend when pulled, said bend producing a concavity in the side of the material having the lesser number of warp threads thereon.

3. A tie lining structure comprising a bias-cut, woven fabric material, said structure including distinctive longitudinal sections, each of said sections including filler threads and warp threads interwoven therewith, a central section of said structure having its warp threads occurring in greater density on one side thereof than on the other, the endwise disposed sections having warp threads occurring in greater density on one side than on the other, said one side of said endwise sections being oppositely disposed to the corresponding side of said central section, the disparity in density of warp threads being operative to produce a bend in said sections when pulled, the bend produced in said central section being opposite to the bends produced in said end sections whereby said structure is given an undulating effect when said structure is pulled.

4. A tie lining structure comprising a bias-cut, woven fabric material, said structure including three distinguishable longitudinal sections, said longitudinal sections being interwoven, each of said sections including filler threads and warp threads interwoven therewith, a central section of said structure having its warp threads occurring in greater density on one side thereof than on the other side, the endwise disposed sections similarly having warp threads occurring in greater density on one side than on the other, both said one sides of said endwise sections being on the same side of the tie lining structure and opposite to said one side of said central section, the disparity in density of warp threads on the sides of each of said sections being operative to produce a bend in said sections when pulled, the bend produced in said central section being opposite to the bends produced in said end sections whereby said structure is given an undulating shape when said structure is pulled, said end sections being tapered and said central section being substantially rectangular, the tapers of said end sections causing said end sections to converge toward one end of said central section.

5. A tie lining structure comprising a bendable material, said structure including three distinctive longitudinal sections, and woven means associated with a centrally disposed section of said structure for imparting a controlled bend thereto, said woven means comprising a disparity in the disposition of threads on the respective sides thereof so as to cause said structure to assume a bend when pulled, said bend producing a concavity in a predetermined one of the sides of said structure, said centrally disposed section and woven means associated therewith being substantially rectangular in shape and the sections on either side thereof tapering in a common direction.

6. A tie lining structure comprising a bendable material, and woven means connected to a centrally disposed longitudinal portion of said structure for imparting a controlled bend thereto, said woven means comprising an elongated strip having filler threads and warp threads interwoven therewith and appearing on either side of said

filler threads, the warp threads on one side of the filler being disposed in greater density than the warp threads on the other side of the filler, said elongated strip being bias-cut, said disparity of warp threads on both sides of said filler being operative to produce a bend in said strip when pulled, said bend being transmitted to said centrally disposed longitudinal portion so as to create a concavity therein.

7. A tie lining structure according to claim 6 wherein the warp threads on said one side of the filler occur with twice the frequency of the warp threads on the other side of the filler.

8. A method of producing tie linings which comprises weaving a length of material in herringbone sections and so as to have a disparity of weaving pattern in successive sections, and making diagonal cuts in every other section of said herringbone sections whereby tie linings are produced having a complete central section and tapering end sections, said end sections being of the same weaving pattern and opposite to that of said central section.

9. A method of producing tie linings which comprises weaving a length of material in herringbone sections and so as to have a disparity of weaving pattern in successive sections, bias-cutting said length of material and making diagonal cuts in every other section of said herring-

10 bone sections, said diagonal cuts tapering toward a common end of said central section whereby tie linings are produced having a complete central section and tapering end sections, said end sections being of the same weaving pattern and opposite to that of said central section.

10. A method of producing tie linings which comprises weaving a length of material in herringbone sections and so as to have a disparity of weaving pattern in successive sections, bias-cutting said length of material and thereafter cutting elongated strips of said material having a central section and end sections on either side thereof, said end sections being of the same weaving pattern and different from that of said central section.
